[57] **CLAIM**

The ornamental design for an opposed tower cable stay
supported roof structure, as shown and described.

DESCRIPTION

FIG. 1 is a perspective view of an opposed tower cable
stay supported roof structure showing my new design;
FIG. 2 is a front elevational view of the structure taken
from the left of the view shown in FIG. 1;
FIG. 3 is a top plan view of the structure; and
FIG. 4 is a side elevational view of the structure.
The broken line showing of a building is for illustrative
purposes only and forms no part of the claimed article.

FIG. 1

FIG. 2

FIG. 3.

FIG. 4.
